UNITED STATES PATENT OFFICE.

EARL R. JOHNSON, OF CHICAGO, ILLINOIS.

RULER.

Application filed September 27, 1926. Serial No. 137,852.

My invention relates to rulers, more particularly to desk rulers for ruling with pencils or writing pens and provided with fiducial ruling edges for such purpose, the main object of my invention being to provide an improved instrument of this character which will embody certain desired features of simplicity, efficiency and convenience, and which will afford a practical, inexpensive advertising medium.

An object of my invention is to provide a ruling instrument characterized by having means in the form of replaceable inserts for carrying advertisements, calendars, combinations thereof, or any printed or written matter which it may be desired to discard and replace from time to time.

A further object of my invention is to provide a ruling instrument in which the means for carrying the replaceable inserts will also serve as means for holding the fiducial ruling edge so spaced from the paper that the ink falling from a writing pen will not be spread and blurred over the ruled lines.

Another object of my invention is to provide a frame construction containing the replaceable insert features and to so arrange the frame construction that it may be employed either as an attachment for the ordinary desk ruler or as a card holder capable of being attached to a trunk, shipping case, or the like.

Other objects will appear hereinafter.

The invention consists in the combinations and arrangements of parts hereinafter described and claimed.

The invention will be best understood by reference to the accompanying drawings, forming a part of this specification, and in which,

Fig. 1 represents a top plan view of a ruler constructed in accordance with my present invention;

Fig. 2 represents a view of a reverse face thereof;

Fig. 3 is a cross section taken on the line 3-3 of Fig. 1;

Fig. 4 is a longitudinal section taken on the line 4-4 of Fig. 1.

Fig. 5 represents a top plan view of a modified construction adapted to be employed as an attachment for an ordinary desk ruler, this view showing the modified

construction as it appears when secured to such a ruler;

Fig. 6 is a longitudinal section taken on the line 6-6 of Fig. 5;

Fig. 7 is a cross section taken on the line 7-7 of Fig. 5;

Fig. 8 represents a top plan view of the modified construction as it appears detached from the ruler and with the information card or strip omitted;

Fig. 9 is a view similar to that of Fig. 8, showing the modified construction as it appears when made in the form of a frame; and,

Fig. 10 is a cross section taken on the line 10-10 of Fig. 9.

Referring with more particularity to Figs. 1 to 4, inclusive, wherein by way of example I have illustrated a preferred embodiment of my invention, the numeral 11 designates a body element made of any suitable sheet metal and provided with a straight or ruling edge 12 with which upon the opposite faces of the body element are associated linear scales 13 and 14, respectively, said scales preferably reading in opposite directions and differing from each other in that they contain different arrangements of inches or fractional parts thereof. The side 15, opposite the straight edge 12, is made with an integral flange 16 which is bent flatwise over one face of the body element. In

a similar manner the opposite ends 17 are provided with integral flanges 18 which are bent flatwise over the same face of the body element. Back a distance from the linear scales, integral flanges 19 are struck from the stock and bent flatwise over the body element and toward the flange 16. The flanges, thus produced, are on the same face of the body element, and provide confronting channels 20 for the reception of a strip

21 which may have any suitable matter printed or written thereon. In the embodiment shown, said strip 21 is shown as provided with a calendar section 22 and an advertising section 23. If desired, a calendar

only may be printed on the strip 21; or, on the other hand, its entire surface may contain advertising matter.

According to an important feature of my present invention, the strip 21 is made of bendable material such as celluloid or paper,

so that it may be readily applied or removed through ways or openings 24, preferably produced by omitting the flanges for this purpose. By this arrangement the bendable strip 21 may be removed and replaced from time to time.

According to another important feature of my present invention, the inturned flanges 16, 18 and 19, serve as rests for supporting the body element with the straight or ruling edge 12 raised from the paper to be ruled. In view of this provision, an ordinary writing pen may be employed in connection with the straight edge 12 without spreading the ink and blurring the ruled lines.

In Figs. 5 to 8, inclusive, I show a modified construction which is capable of use as an attachment for an ordinary desk ruler 25. In this construction, the sides and ends 20 of the body element 26 are made respectively with inturned side and end flanges 27 and 28 so as to produce confronting grooves for the reception and retention of a flexible strip 29. As in the previous form, the side flanges 25 are interrupted to provide opposing ways 30 through which the advertising strip may be entered or removed. The body element 26 is provided with suitable openings 31 for the reception of screw elements 32 by which the 30 body element may be secured in place upon the ruler 25.

In Figs. 9 and 10 I show another modification suitable for use as an attachment. In this embodiment, the construction includes a frame composed of opposing sides 33 and opposing ends 34, which sides and ends are made with integral flanges 33' and 34', respectively, for retaining the advertising strip. The side flanges 33 are suitably 40 interrupted to provide opposing ways 35 through which the advertising strip may be applied or removed. In this construction, the opposing sides 33 are connected by strengthening webs 36 in which are produced the openings 37 for the reception of the screw elements by which the attachment may be secured to the ruler. By making the device in the form of an attachment, it is capable of being used not only in connection

with a common desk ruler but also in connection with a trunk or other carrying receptacle on which it may be desired to change the identification card from time to time.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A ruler construction comprising a body element having a ruling edge; and confronting flanges on said element arranged to hold an insert in place thereon, one of said flanges being struck out of the body element inwardly of said ruling edge, and being interrupted to provide ways for the replacement of said insert, substantially as described.

2. A ruler construction comprising a body element having a ruling edge and provided with a linear scale and four flanges on said element bent flatwise thereover to receive and retain an information insert on said element; said flanges affording rests for said element to support the ruling edge thereof spaced from the paper to be ruled; and certain of said flanges being interrupted to provide ways for the replacement of said insert, substantially as described.

3. A ruler construction comprising a sheet metal body element having a ruling edge and linear scales on its opposite faces along said ruling edge; flanges bent from the stock of the body element and jointly comprising means for holding an insert in place thereon; certain of said flanges being struck out of the stock inwardly of the linear scales on the opposite faces of the body element, substantially as described.

In testimony whereof I have signed my name to this specification.

EARL R. JOHNSON.
